UNITED STATES PATENT OFFICE.

MILTON H. COOK, OF SAN FRANCISCO, CALIFORNIA.

PACKING AND METHOD OF PREPARING IT.

Application filed August 10, 1921. Serial No. 491,142.

To all whom it may concern:

Be it known that I, MILTON H. COOK, a citizen of the United States, residing in the city and county of San Francisco and State 5 of California, have invented new and useful Improvements in Packings and Methods of Preparing Them, of which the following is a specification.

This invention relates to packing members and particularly pertains to cup leathers and the like.

It has been impossible to use rawhide in the manufacture of cup-shaped packing leathers or leather pressed in various 15 shapes due to the fact that rawhide is soft of itself and would not remain in shape.

It is the principal object of the present invention therefore to provide a packing embodying the desirable qualities of a raw 20 hide wearing surface and the stiffening properties of other leathers.

It is also the object of the invention to provide a packing which is reinforced at the heel as shown in the accompanying 25 drawing. This is the point at which most cup leathers wear out, due to the fact that the follower forming part of the mould usually presses the leather very thin at that point, weakening it. The rawhide used 30 in the invention reinforces the leather at this point and prevents it from breaking there, and also provides a self-expanding and self-lubricating surface.

The present invention contemplates the 35 use of packing, the friction surface of which is formed of rawhide united to a packing of other leather, such as oak tanned leather, against which heavy and objectionable pressures will be delivered.

40 The invention is illustrated by way of example in the accompanying drawing in which the figure is a view in transverse section through a cup leather with which the present invention is concerned.

45 Referring to the drawing 10 indicates an inner leather backing preferably formed of oak tanned leather and over which backing an outer layer 11 of raw hide leather is applied. In the past, raw 50 hide has been used for packing material for stuffing boxes and the like, in which case it has been braided.

In the past, in attempting to manufacture raw hide packing cups it has been found 55 that due to the soft pliable nature of the raw

hide it does not retain its shape and would be ruptured by the excess pressures to which it is subjected. The drawing, therefore, shows the application of the invention to the manufacture of cup leathers, 60 although it is to be understood that various other products might be formed along the same general line, without departing from the spirit of the present invention.

In making products of the character described, it is first desirable to cement the raw 65 hide onto the piece of oak tanned leather. This is preferably done by a cement made from celluloid dissolved in acetone. After the two leathers and their cement have thoroughly dried and set, the leather is wetted 70 down and pressed into cup shape by any of the usual methods. The formed cups are then allowed to dry in the mold and, if necessary, the outer layer, which will be 75 raw hide, may then be treated with a desired lubricant while the inner layer of oak tanned leather is impregnated with shellac, paraffine, or any other similar desirable substance, the idea being to stiffen the backing 80 of oak tanned leather and to render the outer raw hide surface both pliable and oily. This will insure that the packing will be what might be termed self-lubricating and, due to its soft and pliable nature, will withstand 85 pressure more satisfactorily than most packing heretofore made.

In some instances it might be found desirable to first extract the oils from the raw 90 hide by means of powerful solvents, such as gasoline, ether or acetone, after which the raw hide is dried and then cemented to the backing of oak tanned leather. In this case it will be necessary to subsequently treat the raw hide with oils so as to restore the fats 95 and oils which have been removed. This treatment will, of course, be brought about after the two thicknesses of leather have been cemented together.

It will thus be seen that by constructing 100 packing members having a wearing surface of raw hide and a backing of stiff tanned leather, it is possible to provide a desirable packing material which is pliable, oily, and at the same time has sufficient strength and 105 rigidity to withstand the stresses to which it is subjected.

While I have described the preferred method and construction of my invention, it is to be understood that various changes in 110

the steps of the process and the arrangement of the parts might be made by those skilled in the art without departing from the spirit of the invention as claimed.

5 Having thus described my invention, what I claim and desire to secure by Letters Patent is:

- 10 1. A packing material comprising a wearing surface of raw hide, a backing of stiff leather, and a binder interposed between the rawhide and the stiff leather.
- 15 2. A packing material comprising a backing of oak tanned leather, over which is cemented a wearing surface of raw hide.
- 20 3. A packing comprising an inner portion of oak tanned leather or other material to which is cemented an outer layer of raw hide, the back being rendered stiff and the raw hide being pliable.
- 25 4. A method of making leather packing which consists in first cementing a layer of oak tanned leather to a layer of raw hide, and thereafter impregnating the oak tanned leather to render it stiff.
5. A method of making leather packing which consists in first cementing a layer of oak tanned leather to a layer of raw hide, and thereafter impregnating the oak tanned

leather to render it stiff, and treating the raw hide to render it oily and pliable. 30

6. A method of preparing leather packing cups which consists in cementing layers of oak tanned leather and raw hide together, thereafter wetting the leather down and pressing it into cups where it is 35 allowed to dry, with the raw hide surface outermost; and then impregnating the inner leather surface to stiffen it.

7. A method of preparing leather packing which consists in cementing layers of 40 oak tanned leather and raw hide, together; thereafter wetting the leather down and pressing it into shape where it is allowed to dry, with the raw hide surface outermost; then impregnating the inner leather 45 surface to stiffen it; and then treating the raw hide surface to render it pliable.

8. A method of preparing leather packing, which consists in extracting the oils from rawhide by solvents, cementing layers 50 of oak tanned leather and the said rawhide together, treating the rawhide to restore the oils and fats extracted therefrom and then impregnating the oak tanned leather to stiffen it.

MILTON H. COOK.
